UNITED STATES PATENT OFFICE.

BENJAMIN F. STEWART, OF CHICAGO, ILLINOIS.

INTERNAL-COMBUSTION ENGINE.

1,146,365.

Specification of Letters Patent. Patented July 13, 1915.

Application filed April 7, 1915. Serial No. 19,622.

To all whom it may concern:

Be it known that I, BENJAMIN F. STEWART, a citizen of the United States, residing at Chicago, in the county of Cook and State 5 of Illinois, have invented a certain new and useful Improvement in Internal-Combustion Engines, of which the following is a specification.

This invention relates to internal combustion engines and has for its object to provide a new and improved engine of this description.

The invention is illustrated in the accompanying drawings, wherein—

15 Figure 1 is a side elevation with parts omitted, of an engine embodying the invention; Fig. 2 is an end view of the engine shown in Fig. 1; Fig. 3 is a sectional view taken on line 3—3 of Fig. 2; Fig. 4 is a sectional view taken on line 4—4 of Fig. 3; Fig. 5 is a sectional view taken on line 5—5 of Fig. 3; Fig. 6 is a sectional view taken on line 6—6 of Fig. 3.

Like numerals refer to like parts throughout the several figures.

For the purpose of explaining my invention, I have illustrated an engine with eight cylinders. In this construction the engine casing is made in three sections 1, 2 and 3, 20 sections 1 and 2 projecting at an angle to each other and placed, as it were, side by side, said sections containing the cylinders of the engine. Each of the sections 1 and 2 is provided at its outer end with the valve 25 casing 4 integral with the section and containing the rotary valve 5 for controlling the admission of the explosive mixture to the cylinders and the discharge of the exploded gases from said cylinders. The two sections 40 1 and 2 have the meeting faces 6 at each end, which are brought together when the sections are united, the sections being clamped together by the rods or bolts 7 and 7^a. These faces are provided with flanges 6^a clamped 45 together by bolts 6^b. The lower part of the casing 3 has at each end an engaging face 8, which engages the engaging faces 9 and 10 of the sections 1 and 2. The engine shaft 12 is mounted in suitable journal boxes at 50 attached to the sections 1 and 2. In the construction shown there are three of these journal boxes, one at each end of the casing, and an intermediate one. The upper parts 13 of these journal boxes are connected with 55 sections 1 and 2, being preferably integral therewith. The lower parts 14 of these jour-

nal boxes are removably connected to the upper parts in any desired manner, as by the bolts 15, extending through lugs 1^a and 2^a on the sections 1 and 2, and the lugs 3^a on the section 3. The journal boxes are provided with suitable lining 16. It will thus be seen that when the section 3 is removed by taking out the bolts 11, the journal boxes remain in position and hold the shaft in position, being supported by the sections 1 and 2. The shaft 12 is provided with four cranks 17. The cylinders are provided with suitable pistons 18, and two pistons in section 1 are provided with the piston rods 19, which are bifurcated at the ends where they connect with the cranks 17; being provided with the two separated branches 20 and 21. Two pistons in the opposite cylinder in section 2 are provided with piston rods with parts 22 encircling the shaft, which fit in between the branches 20 and 21 of the piston rods 19 and connect with the crank between said branches. The shaft encircling parts of the branches 20 and 21 engage the wearing 80 part 22^a on the crank, while the parts 22 engage a sleeve 22^b. It will thus be seen that the wearing face of the part 22 is at a greater distance from the center than the wearing faces of the parts 20 and 21, thereby tending to equalize their wearing faces due to the fact that there is only one encircling part 22, while there are two encircling parts connected with the branches 20 and 21. The other pistons in section 1 are provided 85 with piston rods which have single parts 22 encircling the shaft, and which fit in between the branches 20 and 21 of the piston rods of the pistons in the opposed cylinders in part 2, said piston rod being similar to 90 the piston rods 19, thereby permitting the eight pistons to be connected with the four cranks, thereby economizing space. The engine may be supported in any desired manner. For purposes of illustration I have 95 shown a convenient means for supporting it in cases where it is used on an automobile or the like. In this construction the sections 1 and 2 are provided at one end with the lugs 25, having screw threaded bolt holes in them. 100 A bar 26 extends across the end of said sections and is bolted to said lugs, the ends thereof resting upon the supports 27, which in an automobile would be the side frame pieces of the chassis. The ends of this bar 110 may be bent in any desired shape so as to reach the supports provided they are not in

proper position when the bar is straight. The bar 26 is connected to the engine frame by the bolts 26^a. At the other end I prefer to provide a single lug 28, and the bar 29 is connected with this lug, the bar 29 being similar to the bar 26. This gives, as it were, a three-point support and permits the engine to properly adjust itself. The sections 1 and 2 are provided with the intake openings 30 and 31, which are connected by the pipes 32 with the carburetor (not shown). The explosive mixture passes through the opening 30 into the chamber 30^a and then through the ports 33 in the valve 5, and then passes through ports 35 into the engine cylinders and the burnt gases are exhausted from the cylinders through the ports 36 into the central chamber 37 of the valve and they are discharged through the discharge pipe 38.

Some means is provided for holding the valve down on its seat. As herein shown, the casing 4 is cut away to receive the rings 39 which engage the valve. These rings are adjusted by means of the adjusting screws 40 so as to press the valve down on its seat and hold it in this position. The screws also permit the valve to be adjusted for wear. I have shown these rings as split ball bearing rings, but they may be formed in any other desired manner. The valve is operated in any desired manner from the engine shaft. As herein shown, there is connected with the valve a sprocket wheel 41 which is connected by a chain 42 to a sprocket wheel on the engine, the two sprocket wheels being properly proportioned to secure the proper movement of the valve. It will be seen that with this construction, by simply removing the lower part 3 of the casing, the engine shaft remains in position and the engine shaft, cranks and piston rods are accessible, and hence it is not necessary to tear down the entire engine to gain access to them in order to repair them or remove them. In view of the fact that the cylinders have the valve casing at the outer ends thereof they can with this construction be easily bored from the inner ends, because when the sections are taken apart the inner ends are free and open.

I have shown in the drawings one method of oiling the central bearing for the shaft 12, this central bearing being within the casing. In this construction an oil hole 43 is located between the two sets of cylinders. (See Figs. 1 and 5). This oil hole communicates with oil ducts 44 and 45, which communicate with grooves 46 in the lining 47 of the journal box. Openings 48 through the said lining conduct the oil to the shaft 12. I use the two ducts 44 and 45 to better spread the oil and also because a single duct cannot be used at the center of the part 49, due to the fact that one of the bolts 7^a passes

therethrough. I prefer to provide the lower part of the casing with an oil reservoir 50. (See Figs. 1, 4 and 5). The oil passes from the crank case into the reservoir 50 through the openings 51. I also prefer to provide the inner face of the crank case with the ribs 52 between which the cranks pass when the engine is in operation, these ribs holding oil so that the cranks will become splashed with oil at each revolution. When the spaces between the ribs become filled with oil, the oil runs over the ribs and then passes through the openings 51 into the oil reservoir. The oil may then be pumped back to the point of use by a suitable pump (not shown). The rotary valves 5 are oiled by means of pipes 53, which pass along the face thereof, and which communicate at intervals with openings 54 leading to the outer face of the valve (See Fig. 6). The two sections 1 and 2, containing the cylinders are arranged so that any one thereof can be used either at the right or left hand side. I also prefer to provide a passageway 55 through the casing of each set of cylinders between the two middle cylinders (see Figs. 3 and 5), the oil passing to the carburetor, passes through one of these passageways while the air passing to the carburetor passes through the other passageway, thereby heating both the oil and the air. These passageways are arranged so that the passageway in either section can be used for either purpose. The casings in the cylinders are provided with the openings 56 and 57 for the entrance and discharge of the cooling water for the water jackets.

The engine can be very easily and cheaply machined and assembled, the only parts requiring to be machined being the faces 6, 9 and 10 of the sections 1 and 2 and the faces 8 of the section 3, said faces being the edges of the walls of the casing at the ends thereof. It will further be noted that when the cylinder sections 1 and 2 are once bolted together they need not be taken apart again as the inside of the cylinders is accessible by simply taking off the bottom part 3. Each section 1 and 2 may be cast with any desired number of cylinders. By this means cheapness of construction and simplicity are secured. It will also be seen that any one of the pistons can be easily and quickly taken out without interfering with any other pistons, by simply taking off the lower part of the crank case and then disconnecting from the shaft the piston rod of the particular piston it is desired to remove.

I claim:

1. An engine comprising a casing having three separate sections, two of the sections containing the cylinders, said cylinders being inclined with relation to each other, the third section forming the bottom of the crank case, bolts passing through the bodies

of the two sections containing the cylinders for connecting them together, and means for fastening the third portion of the casing to the other two.

- 5 2. An engine comprising a casing having three separate sections, two of the sections containing the cylinders, said cylinders being inclined with relation to each other, the third section forming the bottom of the 10 crank case, bolts passing through the bodies of the two sections containing the cylinders for connecting them together, means for fastening the third portion of the casing to the other two, a shaft passing through the 15 casing, said shaft supported upon the two sections containing the cylinders, whereby the third section may be removed without interfering with the shaft and the other two sections.
- 20 3. An engine comprising a casing having three separate sections, two of the sections containing the cylinders, said cylinders being inclined with relation to each other, the third section forming the bottom of the casing, a crank shaft extending through said casing, means for supporting the crank shaft on the two sections containing the cylinders, and means for removing the third section without displacing said crank shaft.
- 30 4. An engine comprising a casing having three separated sections, two of the sections containing the cylinders, said cylinders being inclined with relation to each other, the third section forming the bottom of the casing, means for connecting the three sections together, the two sections containing the cylinders being reversible so that either section 35 can be used as a right or left section.
5. An engine comprising a casing having 40 three separate sections, two of the sections containing the cylinders, said cylinders being inclined with relation to each other, the third section forming the bottom of the crank case, means for connecting the three 45 sections together, a crank shaft extending

through the casing, an inner bearing for said crank shaft, the casing provided intermediate the cylinders, with oil ducts leading to said bearing.

6. An engine comprising a casing having 50 three separate sections, two of the sections containing the cylinders, said cylinders being inclined with relation to each other, the casing of each of said two sections intermediate the cylinders having a passageway 55 therethrough, one passageway for the air that goes to the carburetor, the other for the oil that goes to the carburetor; so that the air and oil may be heated, the third section forming the bottom of the crank case, and 60 means for connecting the three sections together.

7. An engine comprising a casing having 65 three separate sections, two of the sections containing the cylinders, said cylinders being inclined with relation to each other, the casing of each of said two sections intermediate the cylinders having a passageway therethrough, one passageway for the air that goes to the carburetor, the other for the oil 70 that goes to the carburetor, so that the air and oil may be heated, the third section forming the bottom of the crank case, means for connecting the three sections together, 75 said sections containing the cylinders being reversible so that either section can be used as a right or a left section, the passageways through said sections being inclined in opposite directions with relation to the vertical plane of the engine so that they are in 80 proper position regardless of the side upon which the sections may be used.

In testimony whereof, I affix my signature in the presence of two witnesses this 26th day of March 1915.

BENJAMIN F. STEWART.
